CLAIM

The ornamental design for a cleaning brush, as shown and described.

DESCRIPTION

FIG. 1 is a front perspective view of a cleaning brush, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof;

FIG. 8 is an enlarged bottom view thereof;

FIG. 9 is an enlarged detail view of are 9 in FIG. 1;

FIG. 10 is an enlarged detail view of are 10 in FIG. 1;

FIG. 11 is an enlarged detail view of are 11 in FIG. 1; and,

FIG. 12 is an enlarged detail view of area 12 in FIG. 1.

The broken lines in the drawings illustrate the portions of the

cleaning brush, which form no part of the claimed design.

The dash-dot-dash broken lines encircling the enlarged

views are for annotative purposes only and form no part of

the claim thereof.

1 Claim, 12 Drawing Sheets
